CRYPTOGRAPHIC MACHINE.

1,196,388.

Specification of Letters Patent. Patented Aug. 29, 1916.

Application filed November 15, 1912. Serial No. 731,592.

To all whom it may concern:

Be it known that we, HARRY A. CORBETT and JAMES WILLARD MORRIS, a subject of the King of Great Britain and Ireland and a citizen of the United States, respectively, residing in the borough of Manhattan, city, county, and State of New York, have invented certain new and useful Improvements in Cryptographic Machines, of which the following is a specification, reference being had therein to the accompanying drawings, which form a part thereof.

Our invention relates to cryptographic machines, and more particularly to a machine which is adapted to convert grammatically correct or code copy into a cipher message, and vice versa.

In order that our invention may be more fully understood, we will first describe, broadly, the general mode of operation of the machine, and will then describe the particular form of machine shown in the drawings, with the operation of this particular machine.

In cryptographs or secret codes, there are two primary essentials, to wit:—that the message must be readily indited and transcribed by means of a key, and the key must be so complex that a message may not be readily deciphered even by those skilled in such matters. In our machine we have endeavored to secure these two results by mechanically assembling the different letters or characters constituting a message, without necessitating any mental labor on the part of the sender; by mechanically transcribing the message in the same manner; and by providing a key which consists solely in an adjustment of this machine. By this means we are not only enabled to greatly expedite the compiling of a cipher message, and the transcription or deciphering thereof, but are enabled to vary the entire code at any time by a mere readjustment of the machine, it being merely necessary that the adjustment be known to the receiver of the message.

In each machine, we employ a movable member having thereon preferably the letters of the alphabet and the punctuation marks, this indicating device being movable, and preferably rotatable. In connection with this movable member, we use selective means whereby any letter or character thereon may be selected and said member so actuated as to normally bring this

letter to place, or impart variable movement thereto in a degree which would normally have this result. In order to have the letter which actually comes into this position, however, differ from that selected by said selective means, we provide means acting upon said movable member, which will impart movement thereto independently of said selective means, thus presenting in the operative position a letter or character differing entirely from that which the selective means is actuated to bring to place. These last named means constantly vary the operative relation of the movable member and the selective means, so that upon each succeeding operation of the machine, even if the independently operative mechanism be inoperative, the letter or character brought to place by said selective means will rarely, if ever, be that selected by said means, although the extent of operation of the selective means will be such as would normally bring the letter indicated thereby to place. Hence the result of the actuation of the machine will be that while the operator, through the selective means defines a certain sequence of letters constituting the words of a message, the movable member will be so actuated as to indicate an entirely different sequence of letters which have no apparent meaning. Inasmuch as in a sequence of operations of the machine, or actuations of the selective mechanism, the same letter will not be repeated regularly, and inasmuch as the actual letters or characters indicated on the cryptogram are arbitrarily brought to position by means independent of said selective means, it is apparent that in a message the same letter will not be likely to be represented by the same character more than once. To still further complicate this condition, we so construct and arrange our machine that the movements of the movable member under the independently operating means acting thereon, are irregular and erratic, this irregularity being under the control of the operator so that the same conditions may be caused to exist in the machine used in transcribing or deciphering the message. By way of example, we may construct our machine so that the movable member will be acted upon by the independently operating means upon the first actuation of said movable member; will not be acted upon for two movements of said movable member; will then be acted upon

twice in succession, and then will not be acted upon for one or more movements of the movable member, etc. The exact order of activity and inactivity of this actuating means may be determined at will by the operator, but this order cannot be determined by anybody unless they have definite information. To guard against any possibility of a code being learned, this order may be changed at the will of the operator at any time, and the entire results of the actuation of the machine modified accordingly.

Another way of modifying or changing the code would be to merely start or set the independent actuating means at an entirely different point from that previously used, thus preserving the original order except as to the initiation thereof. As for example, instead of having the independent actuating means operative upon the first actuation of the indicating means, said independent means may be rendered inoperative upon the first actuation of the movable member; be actuated twice in succession following, and so on in the same order as in the first instance, the relative order of actuation being resumed after one complete cycle of said independent actuating means.

In fact by very slight adjustments of the machine, the different combinations of letters resulting from its actuation may be varied infinitely, and changed so quickly that it is practically impossible by comparison or by any of the ordinary laws or rules governing the deciphering of cryptograms, to determine or fix upon any key by means of which a message may be deciphered.

By reversing the order of the letters or characters upon the movable member, and the movements imparted to said movable member under said selective means, and causing the independent actuating means to act upon said movable member in the same manner as in operating the movable member in formulating the cipher, or by actuating the movable member in the same direction as the selective means, and reversing the operative effect of the independently operative means upon said movable member, the erratic movement of said movable member may be duplicated in the reverse, assuming of course, that all of the operative parts of the machine including said movable member and said independent actuating means, are set as in formulating the cipher, and the original message or the letters originally selected by the selective means, may be brought to place to transcribe the cipher message. For example, if in formulating the message, the letter j is selected by means of the selective means, this letter j will be first brought to place by the selective means, but the independently operating means acting upon the indicating means will impart to said movable member additional movement

so as to shift the means to bring the letter z to place. Thus, while the letter j has been selected, the result of this selection is to present to the operator in the cryptogram, the letter z. In transcribing, however, the operator will select the letter z which appears upon the cipher, and by moving the movable member in the opposite direction will bring this letter to place. The subsequent actuation of the movable member by the independently operative means, however, will again shift the movable member so that instead of the letter z appearing to the operator, the letter j will appear in its stead.

Inasmuch as the independent actuating means shifts the position of the movable member each time said means are operative thereon, it is apparent that with the succeeding actuation of the various selective means, the movement of the movable member will be such as would normally tend to bring the letter or character thereon corresponding with the selective device actuated to place, but that this will not actually occur because of the various displacements of said movable member during the prior operation of the machine. In other words, the movable member must be capable of movement under the selective device to a variable predetermined extent, according to the letter or character selected. With each actuation of the independent operating means, however, the relative position of the movable member and of the selective means is varied so that while with the actuation of any selective means, the movable member is actuated to a certain predetermined extent, the result is that the letter brought to place will not correspond with that selected by said selective means.

In the accompanying drawings, we have shown the invention applied to a certain well known type of typewriting machine, in connection with which type of machine our invention has peculiar adaptability.

The invention is not limited in its use, however, to this particular type of machine, and the showing of the drawings is merely for the purpose of illustrating one, and the preferred application of the invention.

Referring to the drawings:—Figure 1 is a perspective view of a mechanism for carrying out our invention; showing those portions of the typewriting machine coöperating therewith; Fig. 2 is a plan view thereof; Fig. 3 is a detail view of the mechanism for actuating the controller; Fig. 4 is a view showing two keys for use upon a machine for both writing and transcribing cipher messages; and Fig. 5 is a detail view of the means for converting the machine from a sending to a transcribing machine.

Like letters refer to like parts throughout the several views.

In the accompanying drawings, we have shown at a a movable member comprising

a rotary type wheel, having two lines of types or characters thereon, the sequence of one of which is the reverse of the other. Carrying and movable with said type wheel 5 is a ratchet wheel *b*. Said type wheel and said ratchet wheel are mounted upon a shaft *c* which also has mounted thereon a star wheel *d* carrying a ratchet *e* acted on by dogs *f* carried by the wheel *b*. The star 10 wheel *d* is keyed to the shaft *c*, and this shaft is actuated by means of type bar, not shown, and the rack and pinion mechanism *f'*, the extent of rotation of said star wheel *d* and ratchet *b* and type wheel *a* varying according 15 to the letter which it is desired to bring to the printing position. At *g* we have shown an ordinary inking mechanism. The detailed actuating mechanism for the star wheel *d* is old and well known in this art, 20 and comprises no part of this invention, and we have therefore shown merely that portion of a machine necessary to show the application of our invention thereto. The ratchet wheel *b* and type wheel *a* are actuated through the pawl and ratchet mechanism *e f* and this mechanism also permits the independent actuation of the said type 25 wheel mechanism to vary the position of the type wheel relative to the star wheel *d* in a manner which will appear more fully hereinafter.

Mounted adjacent to and normally below the star wheel *d* is a reciprocating slide *h* adapted to be forced outwardly into position where it will be engaged by the ratchet *b* after said ratchet and the type wheel *a* have been rotated to the extent determined by the actuation of the mechanism *f'*, this 30 slide being adapted to vary the position of the type wheel *a* and ratchet *b* relative to the star wheel *d* a distance equaling the space of one letter with each engagement of its operative parts.

Mounted adjacent to the slide *h* is a 35 ratchet wheel *i* which contains teeth corresponding in number with the number of characters contained in each sequence of letters or characters upon the wheel *a*. Acting upon said ratchet wheel is a spring- 40 pressed pawl *j* mounted upon a reciprocating carrier *j'* which carrier receives one impulse through the member *j²*, with each oscillatory movement of the shaft *c*. This impulse is against the tension of the spring 45 *j⁵* which is acted upon by the plunger *j⁶*, this spring *j⁵* restoring the carrier *j'* to normal after each actuation thereof from said member.

To prevent an overrunning of the ratchet 50 *i*, we provide a detent pawl *j³* carried upon a spring shank under the control of the adjustment screw *j⁴*.

Rotatable with the ratchet *i* is a controller 55 disk *k*, the periphery of which is divided into sectors corresponding in number with

the number of teeth upon the ratchet *i* and the number of characters in each sequence upon the wheel *a*. About the periphery of this controller disk *k* a sequence of notches are formed, the location and nature of which 70 notches is variable to any desired extent.

To permit the operator to vary the arrangement of these notches, we divide the periphery of the controlling plate *k* by means of a sequence of saw cuts, spaced at 75 equal distances apart, so that the notches may be formed by removing the metal between any succeeding saw cuts. In other words, the controlling disks may have the number of notches about the periphery of 80 same increased at will by the operator, thus changing the entire sequence or order of notches by merely breaking out a portion of the periphery of said disks as defined by two succeeding saw cuts. This controlling 85 disk *k* is the element which imparts the erratic, independent variable movement to the type wheel or indicating device, and by means of the controlling disk *k*, the number of combinations or codes which may be produced by varying the relation and number 90 of notches is infinite.

To permit the removal of one controlling disk *k* and the substitution of another, we mount this disk as well as the ratchet wheel 95 *i* by means of a pivot screw *l* passing through a slot in the slide *h*. The outer end of the slide *h* is provided with an anti-friction roller *h'*, adapted to enter any of the notches about the periphery of the disk 100 *k*, and thus permit a forward thrust of the slide *h* under the control of the spring *m* which will bring the forward end of this slide into position to be engaged by the ratchet wheel *b* upon the reciprocating 105 movement of the shaft *c*.

When using our invention in connection with a typewriting machine employing a type wheel, two series of letters or characters occupying parallel lines and having the 110 same sequence but in a reverse order, are employed. In inditing, one row of these letters or characters is used, and in transcribing or deciphering, the other row is used, the wheel being shifted in the same 115 manner as is ordinarily employed for bringing upper or lower case letters into the printing position with this type of machine. This mechanism is old and well known in the art, and in Fig. 5 of the drawings, we have shown such a mechanism which comprises a pivotal arm *n* adapted to engage the lower end of the shaft *c* to move it and the wheel axially thereof. This rocking arm is actuated by the lever *n'* under 120 the control of the shift key *n²*. At *o* we have shown an old and well known locking means by means of which the machine may be set for either line of keys.

The operation of the herein described de- 130

- vice is substantially as follows, reference being had particularly to the specific form of mechanism shown in the drawings, which however, is not essential to our invention:
- 5 In inditing a communication of any kind, the message may be put in proper grammatical form, or code words may be used, as desired, whether this form be merely a mental process or a presentation of the 10 original message. The letters of the original message in their order are then used in actuating the selective means, or the keyboard of the machine, as indicated in Fig. 4. As each key lever is depressed, the movable member or type wheel *a* which normally is set so as to cause the actuation of any key to bring the letter corresponding with that key to the printing position, is rotated to an extent which under normal 15 conditions would bring this letter to the printing position. In other words, the movements of the type wheel under the control of the several keys, is the normal operation of a machine of this character. This 20 rotation of the type wheel occurs during the first portion of the down stroke of said wheel, the ratchet *d* and shaft *c* being locked prior to the latter or printing portion of the stroke of the wheel. During this down 25 stroke, the controlling means or disk *k* is actuated through the ratchet *i* pawl *j* and carrier *j'* under the control of the member *j²*, thus rotating this disk *k* one notch with each reciprocatory movement of the type 30 wheel. If by this rotation of the disk *k* one of its notches is brought to a position where the slide *h* will be projected by the spring *m* into the path of the ratchet wheel *b* simultaneously with, or prior to the initiation 35 of the latter or printing portion of the down stroke of the said type wheel, while with the first letter at the actuation of this stroke the letter selected by the selective means will be in the printing position, the completion 40 of this portion of the stroke will cause a rotation of the ratchet wheel *b* and with it the type wheel *a* one letter space, thus causing the letter printed to differ from that selected, and throwing the type wheel out of position one letter space. Upon the restoration of the type wheel to normal, this wheel will therefore be so positioned relative to its actuating means that the operation of the latter, or of any key thereof, will impart the normal movement to the type wheel, but will not bring the letter indicated by that key to the printing position. Upon the successive actuation of the selective means, this operation will be repeated according to the location and arrangement of the notches about the disk *k*. Sometimes the type wheel will receive movement in excess of that received from the actuation of its controlling means, or type keys, and at other times it will receive

only the movement imparted thereto by this means. The periods of actuation of the type wheel under the slide *h* will vary according to the arrangement of the notches, and as there are twenty-eight such notches, 70 one for each character, or as any multiple of twenty-eight may be used, upon this disk, it will be seen that a great variety of combinations may be secured. Furthermore, by merely shifting the disk *k* one or more 75 spaces, an entirely different combination may be secured, thus multiplying the first combination by the number of times which this disk may be shifted, it being understood that the shifting of the disk not only 80 varies the first letter of the code, but also all of the subsequent characters during each rotation of this disk. Similarly, variance of the code may be secured by substituting a disk having a different arrangement or 85 sequence of notches or recesses, thus again multiplying the capacity as to variation of the code.

Another mode of changing the code would be by turning the wheel *a* itself one or more 90 spaces.

It will be observed that the determination of the code is thus entirely mechanical, and that no fixed rule of solution can be determined.

In transcribing the cipher, it is merely necessary to reverse the process heretofore described. In the machine shown in the drawings, when transcribing, the disk *k* is set in the same manner as in inditing the 100 message, and the type wheel *a* is set in the same position. The positioning of these parts is all that is necessary for the receiver to know in order to transcribe or decipher the message, and without this knowledge, it 105 is impossible for the message to be transcribed or deciphered.

Let us assume that the sender and the receiver understand that a disk of a certain number is to be used, and set at a certain 110 point, and that the type wheel is always to be set at normal. With this information, a message may be sent and deciphered without danger of being deciphered by those not having this information. If it be desired 115 to change the disk *k* or to change the setting of this disk or of the type wheel, separate advices may be forwarded or separate code words may be used to indicate the setting point, and in fact an infinite number 120 of combinations may be arranged in advance between the sender and receiver, which will provide for the frequent changes of code, and these changes may be accomplished in a fraction of a minute and without reference to code books or the exercise 125 of any great mental effort.

In a machine such as we have shown in the drawings, the type wheel *a* is turned in one direction for certain letters and in the 130

other direction for other letters, and as it is necessary that the movement of this indicating device or wheel *a* should be reversed in transcribing or deciphering by the controlling means, I secure this result by the use of the reversely arranged sequence of letters or characters, and the use of a double set of letters upon the keys. In Fig. 4 I have illustrated this structure. If the letter *j* to the right be selected in sending, it would turn the wheel *a* to a predetermined extent to the right, but in transcribing, the letter *j* to the left would be used, which would turn the said wheel to the left to the same extent. The series of letters being reversed in their order, the subsequent actuation of the type wheel *a* by the plate *h* would turn the type wheel *a* one space, which would bring the letter next to *j* to the printing position, which letter would correspond with the corresponding letter in the original, grammatically correct, or code word. This arrangement is necessary in the type of machine shown in the drawings, as the quantity of movement of the type wheel must be the same in sending as in transcribing, and the direction of movement must be reversed.

The reverse sequence of the transcribing series of letters upon the wheel *a* in the form of the invention shown in the drawings, is made necessary by the fact that the slide *h* both in inditing and transcribing, turns the wheel *a* in the same direction. By this arrangement of the transcribing letters or characters, the same result is secured as through the actuation of the wheel *a* in the opposite direction by the slide *h*, and at the same time, one and the same machine is adapted for use in both inditing and in transcribing.

In the accompanying drawings, we have shown merely one application of our invention, and it is not our intention to limit our invention to this particular type of machine; it being apparent that the underlying principles of our invention may be readily applied to different types or characters of machines, without departing from the spirit and scope of our invention.

Having described our invention, what we claim as new and desire to have protected by Letters Patent, is:—

1. A cryptograph machine embodying therein a reciprocatory support a movable member having thereon a sequence of letters or characters rotatably mounted upon said support, selective means having a sequence of letters or characters co-inciding with those upon said movable member whereby pre-determined successive rotary movements of variable degrees may be imparted to said movable member and a reciprocatory movement is imparted to said support, means adapted to impart rotary movement to said

movable member independently of said selective means, a controlling device whereby said last named means is made intermittently operative and operative connections between said selective means and said controlling device. 70

2. A cryptograph machine embodying therein a reciprocatory support a movable member having thereon a sequence of letters or characters rotatably mounted upon said support, selective means having a sequence of letters or characters co-inciding with those upon said movable member, means actuated by said selective means respectively for imparting variable pre-determined successive rotary movements to said movable member and reversing said rotary movement of said member a reciprocatory movement is imparted to said support, means adapted to impart movement to said movable member independently of said selective means before said member is brought to the first operative position thereby, a controlling device for automatically determining the operative interval of said last named means 90 and operative connections between said selective means and said controlling device whereby the movements of said controlling device are synchronized with those of said movable member. 95

3. A cryptograph machine embodying therein a movable member having thereon two similar sequences of letters or characters, the order of the letters or characters in one sequence being the reverse of that of the other, two groups of selectively operative members, operative connections between each of said groups and said movable member whereby the actuation of one group will impart movement to said member in one direction and the actuation of the members of the other group will impart movement thereto in the other direction, means adapted to impart movement to said movable member independently of any of said selective members, a controlling device whereby said last named means is made intermittently operative and operative connections between said selective means and said controlling device. 110

4. A cryptograph machine embodying therein a reciprocatory support a movable member having thereon a sequence of letters or characters rotatably mounted upon said support, selective means having a sequence of letters or characters co-inciding with those upon said movable member whereby pre-determined successive rotary movements of variable degrees may be imparted to said movable member and a reciprocatory movement is imparted to said support, means adapted to impart rotary movement to said movable member independently of said selective means, a rotatable controlling device having a plurality of irregularly arranged 130

operative surfaces thereon whereby said last named means is actuated and operative connections between said rotatable device and said selective means.

5. A cryptograph machine embodying therein a reciprocatory support a movable member having thereon a sequence of letters or characters rotatably mounted upon support, selective means having a sequence of letters or characters co-inciding with those upon said movable member whereby predetermined successive rotary movements of variable degrees may be imparted to said movable member and a reciprocatory movement is imparted to said support, means adapted to impart rotary movement to said movable member independently of said selective means, a rotatable controlling device having a plurality of irregularly arranged operative surfaces thereon whereby said last named means is actuated, operative connections between said rotatable device and said selective means and means whereby said controlling device may be shifted in relation to its actuating means to vary its operative effect.

6. A cryptograph machine embodying therein a reciprocatory support a movable member having thereon a sequence of letters or characters rotatably mounted upon said support, selective means adapted to impart reciprocatory movement to said support and rotary movement to said member in both directions to said support and to said member, a slide adapted to be projected in the path of said movable member during the reciprocatory movement of said support whereby rotary movement is imparted to said member independently of said selective means, a controlling device whereby said slide is intermittently actuated and connections between said controlling device and said selective means.

7. A cryptograph machine embodying therein a reciprocatory support a movable member rotatably mounted on said support and having thereon two similar sequences of letters or characters, the order of the letters or characters in one sequence being the reverse of that of the other, two groups of selectively operative members, operative connections between each of said groups and said movable member whereby the actuation of the members of one group will impart movement to said rotatable member in one direction and the actuation of the members of the other group will impart movement thereto in the other direction and to impart a similar return movement thereto, means adapted to impart a movement to said reciprocatory support, a slide adapted to be projected in the path of said movable member during the reciprocatory movement of said support whereby rotary movement is imparted said rotatable member independ-

ently of said selective means, a controlling device whereby said slide is intermittently actuated and connections between said controlling device and said selective means.

8. A cryptographic machine embodying therein a controlling device consisting of a circular disk having a peripheral bearing surface, said surface being interrupted by one or more notches, said disk having an opening extending therethrough whereby it may be detachably connected with a rotatable support.

9. A cryptographic machine embodying therein a controlling device consisting of a disk having a peripheral bearing surface, the edge of said disk being provided with a sequence of equi-distant narrow recesses whereby the edge of said disk intermediate said recesses may be readily removed to permit the user thereof to interrupt the bearing surface of said disk by means of one or more notches.

10. A cryptograph machine embodying therein a reciprocatory support, a member having a series of letters or characters rotatably mounted on said support, selective means whereby said support is reciprocated to a uniform extent with the actuation of any member of said selective means to make an imprint therewith, means imparting variable rotative movement to said rotary member, the extent of said movement being determined by the different members of said selective means, and means operative after the termination of the rotative movement of said rotary member, whereby said member receives rotary movement independently of said selective means.

11. A cryptograph machine embodying therein a reciprocatory rotary member having a series of letters or characters, selective means whereby said rotary members is reciprocated to a uniform extent with the actuation of any member of said selective means to make an imprint therewith, means imparting variable rotative movement to said rotary member, the extent of said movement being determined by the different members of said selective means, means operative after the termination of the rotative movement of said rotary member, whereby said member receives rotary movement independently of said selective means, and controlling means for said last named means, whereby said last named means are rendered operative at certain predetermined intervals only.

12. A cryptograph machine embodying therein a reciprocatory, rotary member having a series of letters or characters, selective means whereby said rotary member is reciprocated to a uniform extent with the actuation of any member of said selective means to make an imprint therewith, means imparting variable rotative movement to

5 said rotary member, the extent of said movement being determined by the different members of said selective means, means operative after the termination of the rotative movement of said rotary member, whereby said member receives rotary movement independently of said selective means, rotary controlling means provided with means whereby the operative movement of said last named 10 means is determined, and means actuated simultaneously with the first part of the reciprocatory movement of said support, whereby said controlling means is actuated with each actuation of said support.

15 13. A cryptograph machine embodying therein a reciprocatory support, a member having a series of letters or characters rotatably mounted on said support, selective means whereby said support is reciprocated 20 to a uniform extent with the actuation of any member of said selective means to make 25 an imprint therewith, means imparting variable rotative movement to said rotary member, the extent of said movement being determined by the different members of said selective means, means operative after the termination of the rotative movement of said rotary member, whereby said member receives rotary movement independently of said selective means, rotary controlling means provided with means whereby the operative movement of said last named means is determined, a ratchet wheel adapted to impart movement to said controlling means, 30 and means acting simultaneously with the first part of the reciprocatory movement of said support, whereby a step by step movement is imparted to said ratchet wheel.

14. A cryptograph machine embodying 40 therein a reciprocatory, rotary member having a series of letters or characters, selective means whereby said rotary member is reciprocated to a uniform extent with the actuation of any member of said selective 45 means to make an imprint therewith, means imparting variable rotative movement to said rotary member, the extent of said movement being determined by the different members of said selective means, means operative 50 after the termination of the rotative movement of said rotary member, whereby said member receives rotary movement independently of said selective means, rotary controlling means, means actuated simultaneously with the first part of the reciprocatory movement of said support, whereby said controlling means is actuated with each actuation of said support, a reciprocatory slide, and coöperating means carried by said 55 controlling means and said slide, whereby at 60 predetermined intervals, said slide will be

caused to actuate said rotary member during the latter part of the reciprocatory movement thereof.

15. A cryptograph machine embodying 65 therein a rotary shaft, a printing wheel having a sequence of letters or characters thereon, a star wheel fixed upon said shaft, a ratchet wheel carried by said shaft and rotatable with said printing wheel, a clutch 70 connecting said star wheel and said ratchet wheel, whereby said ratchet wheel and said star wheel are caused to rotate in unison, and said ratchet wheel and said printing wheel are permitted to rotate independently 75 of said star wheel, selective means whereby said star wheel receives variable rotative impulses, and means coöperating with said ratchet wheel whereby said ratchet wheel and said printing wheel receive movement at 80 predetermined intervals, independently of said star wheel.

16. A cryptograph machine embodying 85 therein a rotary shaft, a printing wheel having two sequences of letters or characters thereon, the order of such letters or characters in one sequence being the reverse of that in the other, a star wheel fixed upon said shaft, a ratchet wheel carried by said shaft and rotatable with said printing wheel, 90 a clutch connecting said star wheel and said ratchet wheel, whereby said ratchet wheel and said star wheel are caused to rotate in unison, and said ratchet wheel and said printing wheel are permitted to rotate independently of said star wheel, selective means whereby said star wheel receives variable rotative impulses, means coöperating with said ratchet wheel whereby said ratchet wheel and said printing wheel receive movement at 95 predetermined intervals, independently of said star wheel, means whereby either sequence of letters may be brought to the printing position, and means whereby said selective means may be used to rotate 100 said shaft in a direction, in transcribing, opposite to that in inditing a message, but to the same extent.

In witness whereof, we have severally affixed hereto our signatures, each in the 110 presence of two subscribing witnesses, this 11th day of November, 1912.
